UNITED STATES PATENT OFFICE.

EDWIN G. HINES, OF DRUMS, PENNSYLVANIA.

TOY FENCE.

Application filed February 3, 1922. Serial No. 533,871.

To all whom it may concern:

Be it known that I, EDWIN G. HINES, a citizen of the United States, residing at Drums, in the county of Luzerne and State 5 of Pennsylvania, have invented certain new and useful Improvements in Toy Fences, of which the following is a specification.

This invention relates to improvements in toy fences such as are employed about 10 Christmas trees or otherwise made use of by children in their play, and one of the primary objects of the invention is to provide a toy fence structure which will simulate a split rail fence when properly set up and arranged.

Another object of the invention is to provide a toy fence which may be conveniently 15 completely knocked down and its parts again assembled as desired or may be folded into a more or less compact form so as to in either event prepare it for shipment or to be stored away when not in use.

Another object of the invention is to provide a novel means for connecting the meeting or overlapping ends of the rails comprising relatively adjacent fence sections 20 which connecting means will permit of relative angular adjustment of the said sections so that the fence as a whole may be arranged 25 in any form found most desirable, and its sections furthermore relatively folded.

Another important object of the invention 30 is to provide novel means for bracing the fence in a set-up position and novel means for establishing connection between the bracing 35 posts of the fence and the rails comprising the fence sections.

In the accompanying drawings:

Figure 1 is a perspective view of the fence 40 structure embodying the invention set up, the gate section of the structure being shown demounted;

Figure 2 is a view partly in elevation and partly in section illustrating in detail the 45 arrangement and construction of the connecting means between two adjacent sections of the fence; and

Figure 3 is a view partly in plan and partly in section of the structure shown in 50 Figure 2.

The fence structure embodying the invention comprises end sections indicated in general by the numeral 1, a plurality of intermediate sections indicated in general by

the numeral 2, and a gate section indicated in 55 general by the numeral 3.

Each section 1 of the fence comprises a plurality of longitudinal parallel rails 4 which at one end extend between post members 5, brads, nails, or other similar fastening elements 6 being driven or secured through the post members 5 and through the said end portions of the rails 4. Preferably the rails 4 at their said ends project a greater or less distance beyond the respective post 60 members 5, and these projecting ends which are indicated by the numeral 7, are designed to interfit with the projecting ends 8 of rails 9 which comprise the gate section 3, a sheet metal strap 10 being formed into a 65 loop and secured at its side portions to the said rails 9 as illustrated in Figure 1. In this manner provision is made for supporting the fence section 3 between the end sections 1 and thus completing the enclosure 70 defined by the fence as a whole.

The adjacent ends of the rails of adjacent ones of the sections 1 and 2 throughout the entire series of sections are interfitted and where they overlap are formed with 75 openings 11. These openings 11 register when the rails of adjacent fence sections are interfitted as shown in Figure 2 of the drawings, and accommodate the fence posts which are indicated in general by the numeral 12. 80 Each of these posts comprises a base 13 and an upstanding post member 14 the upper end portion of which is preferably threaded as indicated by the numeral 15. The post 85 members 14 may be made of wire or small rod material and are united at their lower ends to the respective bases 13 in any suitable manner, these bases being for example of circular disk-like form. The post members 14 fit sufficiently freely in the openings 90 11 in the rail ends to provide for relative pivotal or angular movement of the fence sections about the posts 12 as pivots, and the said rail ends of the fence sections are held 95 assembled with the posts by means of nuts 16 which are threaded onto the upper ends 100 15 of the said posts and engage or substantially engage the uppermost rail of the joined sections. In the manner just described, the several sections 1 and 2 are 105 connected end to end and may be relatively disposed at various angles so as to impart to the structure as a whole, when set up, any de-

sired shape or outline. The gate sections 3 completes the enclosure and may be disposed in place upon the projecting ends 7 of the rails of the end sections 1 or may be taken down whenever desired.

In order to adapt the structure to simulate a split rail fence and furthermore to provide means whereby the structure may be braced in position when set up, means is 10 provided which will now be described.

The means above referred to comprises a pair of post members indicated by the numeral 17 and provided with beveled lower ends 18 having perforations 19 through 15 which securing elements such for example as nails or tacks 20 may be driven for the purpose of securing these ends to the floor or other surface upon which the fence structure is set up. The post members 17 are connected in relatively crossed relation at their 20 upper portions by means which is adapted to also establish connection between these members and the fence sections with which they are associated, and this means comprises, in each instance, a coiled spring 21 having its terminal portions fitted through openings 22 formed diametrically in the members 17, the extremities of the said portions of the spring being bent to partly embrace the members 17 as indicated by the 25 numeral 23. In assembling the bracing post members 17 with the fence sections 2, the end portions of the upper rails of the fence sections are fitted into the coiled springs 21 as best shown in Figures 2 and 3 of the 30 drawings and with the said post members 17 straddling the fence sections at their juncture. The upper end portions of the posts 14, when fitted through the uppermost 40 rails of the fence sections, project between the convolutions of the springs 21 and in this manner the springs are retained in place upon the said upper rails. At this point it will be evident that any relative 45 angular movement of the members 17 will be against the tension of the spring 21 and therefore when the lower ends of these members 17 are relatively separated a greater or less distance, the springs will be tensioned, and the said lower ends may then be tacked or otherwise secured to the surface upon which the structure is set up. This 50 tensioning of the connections between the parts serves to more firmly brace the structure than would otherwise be possible, and therefore the structure throughout its entire length will be substantially rigidly supported and braced. The springs 21 may of course be adjusted longitudinally upon the 55 uppermost rails of the fence sections and the upper ends of the posts 14 may be en-

gaged between any selected two of the convolutions of the respective spring 21. If desired, other rails, indicated by the numeral 24 may be loosely laid between the crossed upper ends of the post members 17 so as to further simulate a split rail fence.

Having thus described the invention what is claimed as new is:

1. In a toy fence structure, fence sections connected at their ends for relative angular adjustment and including rails, and a bracing post structure comprising crossed post members and means mutually connecting said members and connected also with one of said rails, the said means comprising a coiled spring anchored at its ends to the post members and having its coils engaging about one of said rails. 70

2. In a toy fence structure, fence sections connected at their ends for relative angular adjustment and including rails, and a bracing post structure comprising crossed post members and means mutually connecting said members and connected also with one of said rails, the said means comprising a coiled spring anchored at its ends to the post members and having its coils engaging about one of said rails, the connecting means for the fence sections comprising a post pivotally fitting through the ends of the rails and passing also through the coils of the spring. 80

3. In a toy fence structure, fence sections embodying rails interfitting at their ends, means extending through the rail ends and connecting the sections for relative angular adjustment, crossed post members disposed to straddle the connected ends of the sections, and a coil spring having its coils fitting one of the rails of one of the sections and having its ends anchored to the said post members and yieldably resisting relative angular adjustment of the said post members. 95

4. In a toy fence structure, fence sections embodying rails interfitting at their ends, means extending through the rail ends and connecting the sections for relative angular adjustment, crossed post members disposed to straddle the connected ends of the sections, and a coil spring having its coils fitting one of the rails of one of the sections and having its ends anchored to the said post members and yieldably resisting relative angular adjustment of the said post members, the lower ends of the post members being beveled and adapted to be secured to a surface upon which the structure is set up. 100

In testimony whereof I affix my signature.
EDWIN G. HINES. [L.S.]
